(57) **CLAIM**

The ornamental design for a rider pallet truck, as shown.

DESCRIPTION

FIG. 1 is a perspective view of a rider pallet truck in accordance with the present invention illustrating our new design, the view taken from the front of the truck;

FIG. 2 is a perspective view of a rider pallet truck in accordance with the present invention illustrating our new design, the view taken from the rear of the truck;

FIG. 3 is an elevational view of the left side of the truck;

FIG. 4 is an elevational view of the right side of the truck;

FIG. 5 is an elevational view of the front of the truck;

FIG. 6 is an elevational view of the rear of the truck; and,

FIG. 7 is an elevational view of the top of the truck.
The broken line showing of a rack and bottom elements in the figures is for illustrative purposes only and forms no part of the claimed design.
